US00D888346S

(12) **United States Design Patent** (10) Patent No.: **US D888,346 S**
(45) Date of Patent: **** Jun. 23, 2020**

(54) **PET FEEDER**

(71) Applicant: **Xinlian Jiang**, Jiangsu (CN)

(72) Inventor: **Xinlian Jiang**, Jiangsu (CN)

(73) Assignee: **Chengdu Saiguo IoT technology Co., Ltd.**, Chengdu, Sichuan (CN)

(**) Term: **15 Years**

(21) Appl. No.: **29/660,846**

(22) Filed: **Aug. 23, 2018**

(51) LOC (12) Cl. **30-07**

(52) U.S. Cl.

USPC **D30/122**

CLAIM

I claim the ornamental design for a pet feeder, as shown and described.

DESCRIPTION

FIG. 1 is a perspective view of a Pet feeder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the pet feeder that form no part of the claimed design but are shown for illustrative purposes.

1 Claim, 7 Drawing Sheets
